**COMBINED VALVE AND ACTUATING HEAD FOR
A GAS LOG LIGHTER**

Joseph T. Leighton, 5245 Topeka Drive, Tarzana, Calif.

Filed May 2, 1963, Ser. No. 74,720

Term of patent 14 years

(Cl. D91—3)

FIG. 1 is a perspective view of a combined valve and actuating head for a gas log lighter showing my new design, the undisclosed side being substantially the same as the side shown;

FIG. 2 is an end view thereof, the undisclosed end being substantially the same as the end shown;

FIG. 3 is a top view thereof; and

FIG. 4 is a bottom view thereof.

The characteristic features of my design reside in the circular actuating head having a flanged cap and square opening in association with the reduced diameter threaded portion and enlarged circular upper portion of the valve, as shown.

I claim:

The ornamental design for a combined valve and actuating head for a gas log lighter, as shown and described.
